UNITED STATES PATENT OFFICE.

JAY H. HALL, OF CLEVELAND, OHIO, ASSIGNOR TO THE ELECTRIC CONTROLLER AND MANUFACTURING COMPANY, OF CLEVELAND, OHIO, A CORPORATION OF OHIO.

CONTROLLER FOR ELECTRIC MOTORS.

1,084,698.

Specification of Letters Patent. Patented Jan. 20, 1914.

Application filed October 16, 1912. Serial No. 726,030.

To all whom it may concern:

Be it known that I, JAY H. HALL, a citizen of the United States, residing at Cleveland, in the county of Cuyahoga and State of Ohio, have invented new and useful Improvements in Controllers for Electric Motors, of which the following is a specification.

My invention relates to controllers for electric motors, particularly that type of controller in which magnetically-operated switches are used to make the proper connections for starting a motor and safely bringing it up to speed.

My invention relates more specifically to an arrangement whereby the motor is first connected to the supply circuit through a transformer and then connected directly to the supply circuit.

One of the objects of my invention is to prevent the connection of the motor directly to the supply circuit until the current in the motor has diminished to a certain value while it is connected through the transformer.

Another object is to effect the change from the starting connection to the running connection without the use of the numerous auxiliary contacts and relays, as heretofore.

In carrying out my invention I provide a magnetically operated starting switch for first connecting the motor to the supply circuit through the transformer, and a second magnetically operated running switch for connecting the motor directly to the supply circuit. The circuit of the winding of the starting switch is controlled by a current limit relay, so that the winding is not de-energized until the current in the motor circuit has diminished to a certain value. The relay has its winding energized by current proportional to that taken by the motor in starting. The relay in operating not only opens the circuit of the starting switch winding, but short circuits a resistance in the circuit of the running switch winding. As soon as the starting switch opens the circuit of the running switch winding is completed and the running switch immediately closes, connecting the motor directly to the supply circuit, whereupon it accelerates to normal speed. I prefer to place the operating winding of the relay in the starting circuit of the motor so that it will be de-energized during the running period of the motor, and I pro-

vide means for delaying the return of the relay to its normal position until the running switch has closed its contacts.

Other objects of my invention will herein-after appear.

Referring to the accompanying drawings, Figures 1 and 2 are wiring diagrams showing two different arrangements embodying my invention.

In these drawings 1 is an electromotor supplied with current through the switch 2. In Fig. 1 a transformer 4 is connected to the supply circuit through the contacts of the switch 5, and the motor is connected to taps on the transformer for starting through the contacts of the switch 6. After the motor has accelerated to a point where the current in the motor circuit has diminished to a certain value, the contacts of the switch 6 are opened and the switch 12 is then closed, connecting the motor through its contacts directly to the supply circuit. The relay 9, which controls the operation of the switches, has its winding connected between the motor and the transformer, but proper operation can be secured by connecting the relay winding between the transformer and the supply circuit, or directly in the motor circuit itself. The relay 9 is that type of relay shown in Eastwood's Patent No. 1,040,292, which is arranged to remain in its unoperated position when the current in the winding is above a predetermined value, and be moved to the operated position by its winding when the current therein diminishes to that value.

I have placed opposite this relay the legend "Lock open," to indicate this type of switch. Upon closure of the master switch 7, the windings 5^a and 6^a of the switches 5 and 6 are energized by the following circuit: from the supply circuit through the master switch 7, and the contacts 12^c which are closed when the switch 12 is opened to the point 13, where the circuit divides, one branch passing through the winding 5^a to the other side of the supply circuit, and the other branch passing through the contacts 9^b which are normally closed when the winding of the relay 9 is de-energized or unoperated, and through the winding 6^a to the other side of the supply circuit. The switches 5 and 6 immediately close their contacts, and current is supplied to the motor through the windings of the transformer 4. Prior to the closure of the switch 6 current flows through

the winding 12^a of the switch 12, the resistance 11, and the contacts 6^b of the switch 6; but the current in the winding 12^a, limited by the resistance 11, is not sufficient to close the switch 12. If the current which flows through the operating winding of the relay 9 exceeds a predetermined value, it locks the relay in its normal position as shown in the drawing; and as the motor increases its speed and the current in the relay winding diminishes, the relay operates to open the contacts 9^b and close the contacts 9^c. The holding winding 9^e on the relay is connected to the supply circuit through the contacts 5 of the switch 5, and is energized upon the closure of this switch, but it has not sufficient energy to cause the relay to operate. It will, however, hold the relay in its operated position after it has been operated by the winding 9^a. As soon as the relay contacts 9^b are opened, the winding 6^a is de-energized, and the switch 6 opens and disconnects the motor from the transformer and de-energizes the relay winding 9^a. The relay, however, remains in its operated position, since the holding winding 9^e is still energized through the contacts of the switch 5. Upon the return of the switch 6 to its open position, its contacts 6^b are closed thereby establishing a circuit through the winding 12^a of the switch 12 as follows: from the supply circuit, through the master switch 7, the winding 12^a, through the contacts 9^c of the relay, and the contacts 6^b to the other side of the supply circuit. The switch 12 immediately closes and connects the motor through its contacts directly to the supply circuit, and the motor accelerates to its normal speed. The closure of the switch 12 opens its auxiliary contacts 12^c, thereby de-energizing the winding 5^a, causing the switch 5 to open and disconnect the transformer from the supply circuit. The holding winding 9^e of the relay is now de-energized, allowing the relay to return to its normal position, opening its contacts 9^e and inserting the resistance 11 in the circuit of the winding 12^a, but the current in the winding is not sufficiently reduced thereby to cause the switch 12 to open. The relay closes its contacts 9^b, but the winding 6^a does not become energized, since its circuit is now opened at the contacts 12^c. To stop the motor the switch 7 is opened, thereby de-energizing the winding 12^a, whereupon the switch 12 opens its contacts, disconnects the motor from the supply circuit, and closes its contacts 12^c, placing the controller in position for restarting the motor upon the closure of the master switch 7.

In Fig. 2, the contacts of the switch 3 connect the transformer 4 to the supply circuit, and also connect the motor to the taps on the transformer. Upon closure of the

switch 2 a circuit is established through the winding 3^a, which goes from one side of the supply circuit through the switch 12^b, the contacts 9^b of the relay, and the winding 3^a to the other side of the supply circuit. A circuit is also established through the winding 12^a, the resistance 11, and the contacts 3^b, but the resistance 11 limits the current in this circuit to a value which is not sufficient to operate the switch 12. The switch 3 by the energy of the winding 3^a, closes its contacts, thereby connecting the transformer 4 to the supply circuit through the contacts 3^c and 3^d, and the motor to the taps on the transformer through the contacts 3^a and 3^e. The relay winding 9^a is energized by the current which passes through the transformer, and if the current in this winding is above a predetermined value, the relay, which is of the same type as the relay shown in Fig. 1, will lock its movable member in its initial position until the current is reduced to that value, whereupon the contacts 9^b will be opened and the contacts 9^c will be closed. The opening of the contacts 9^b de-energizes the winding 3^a, whereupon the switch 3 opens its contacts and disconnects the motor from the transformer. Upon the closure of the contacts 3^b, the winding 12^a is fully energized, the limiting resistance 11 being short-circuited by the relay contacts 9^c. The switch 12 now closes its contacts, connecting the motor directly to the supply circuit, whereupon the motor accelerates to its normal speed. The switch 12 in operating opens the contacts 12^b, thereby preventing the flow of current through the winding 3^a upon the closure of the relay contacts 9^b when the relay returns to its initial position. In order to prevent the relay from opening its contacts 9^c immediately upon the de-energization of its operating winding by the opening of the switch 3, I provide a dashpot 9^d for causing the relay to slowly return to its initial position, thereby giving the switch 12 ample time to close its contacts before the resistance 11 is reinserted in the circuit of the winding 12^a. The resistance 11 is so proportioned that, when it is connected in the circuit of the winding 12^a, the switch will not close its contacts from the open position, but will hold its contacts closed, if the resistance is inserted in the circuit of the winding after the contacts are once closed. To stop the motor, the switch 2 is opened, whereby the motor is disconnected from the supply circuit, the winding 12^a is de-energized, and the switch 12 opens its contacts and closes the contacts 12^b, placing the controller in a position for the next operation in starting the motor.

I claim—

1. The combination of an induction motor,

a supply circuit, a transformer, a starting switch for connecting the motor to the supply circuit through the transformer, an operating winding therefor, contacts in series with the winding, and an operating coil for the contacts energized by current through the motor.

2. The combination of an induction motor, a supply circuit, a transformer, a starting switch for connecting the motor to the supply circuit through the transformer, a running switch for connecting the motor directly to the supply circuit, operating windings for the said switches, a resistance in series with the running switch winding, switch contacts for short circuiting the resistance, and an operating winding for the switch contacts energized by current through the motor.

3. The combination of an induction motor, a supply circuit, a transformer, a starting switch for connecting the motor to the supply circuit through the transformer, a running switch for connecting the motor directly to the supply circuit, operating windings for the said switches, switch contacts in series with the windings, and an operating winding for the switch contacts energized by current through the motor.

4. The combination of an induction motor, a supply circuit, a transformer, a starting switch for connecting the motor to the supply circuit through the transformer, a running switch for connecting the motor directly to the supply circuit, operating windings for the said switches, contacts in series with each winding controlled by the other winding, and contacts in series with each winding operated by a winding energized by the motor current.

5. In an induction motor controller, in combination, a starting switch, a running switch, operating windings therefor, a relay having a winding energized by current in the motor circuit upon the closure of the starting switch, contacts in the circuit of the starting switch winding normally closed by the relay, normally open contacts in the circuit of the running switch winding closable by the relay when operated, means for deenergizing the relay winding before the closure of the running switch, and means for preventing the immediate return of the relay to its normal position when its winding is deenergized.

6. The combination of an induction motor, a supply circuit, a transformer, magnetically-operated contacts for connecting the motor to the supply circuit through the transformer, means automatically operated for opening the said contacts only when the current taken by the motor in starting is below a certain value, magnetically operated contacts for connecting the motor directly to

the supply circuit, and means controlled by 65 the motor current and by the opening of the first contacts for causing the closure of the second contacts.

7. In combination, an induction motor, a supply circuit, a transformer, magnetically-operated contacts for first connecting the motor to the supply circuit through the transformer and then connecting the motor directly to the supply circuit, a relay having 70 normally closed contacts for controlling the connection of the motor to the transformer, and normally open contacts for controlling the connection of the motor directly to the supply circuit, the relay moving its contacts to their operated position only when the 75 starting current of the motor is below a certain value, and means for holding the contacts in their operated position after the motor is disconnected from the transformer.

8. In combination, an induction motor, a supply circuit, a transformer, magnetically-operated contacts for first connecting the motor to the supply circuit through the transformer and then connecting the motor directly to the supply circuit, a relay controlling the connection of the motor to the transformer and the connection of the motor to the supply circuit, an operating winding therefor energized by current through the transformer, and a holding winding for the 95 relay adapted to be connected to the supply circuit.

9. In combination, an induction motor, a supply circuit, a transformer, magnetically-operated contacts for first connecting the 100 motor to the supply circuit through the transformer and then connecting the motor directly to the supply circuit, a relay having normally closed contacts for controlling the connection of the motor to the transformer, 105 and normally open contacts for controlling the connection of the motor directly to the supply circuit, an operating winding for the relay energized by current through the transformer, and a holding winding for the 110 relay connected to the supply circuit.

10. The combination of an electric motor, a supply circuit, a transformer, a starting switch for connecting the motor to the supply circuit through the transformer, a running switch for connecting the motor directly to the supply circuit, operating windings for the said switches, a relay for causing the opening of the starting switch and the closing of the running switch, an operating winding therefor energized by current in the motor circuit, means for deenergizing said winding when the starting switch opens, and means for holding the relay in its operated position until the running switch is closed.

11. The combination of an electric motor, a supply circuit, a transformer, a starting

- switch for connecting the motor to the supply circuit through the transformer, a running switch for connecting the motor directly to the supply circuit, operating windings for the said switches, a relay for causing the opening of the starting switch and the closing of the running switch, an operating winding therefor energized by current in the motor circuit, means for de-
10 energizing said winding when the starting switch opens, and a shunt winding for the relay for holding it in its operated position.
12. The combination of an electric motor, a supply circuit, a transformer, a starting switch for connecting the motor to the supply circuit through the transformer, a running switch for connecting the motor directly to the supply circuit, operating windings for the said switches, relay contacts in the circuits of said windings, and a winding for the relay connected in the motor circuit.
13. The combination of an electric motor, a supply circuit, a transformer, a starting switch for connecting the motor to the supply circuit through the transformer, a running switch for connecting the motor directly to the supply circuit, operating windings for the said switches, relay contacts in the circuits of said windings, and means for operating said relay contacts only when the current in the motor circuit is below a pre-determined value.
14. In an induction motor controller; in combination, a starting switch, a running switch, operating windings therefor, a relay having a winding energized by current in the motor circuit upon the closure of the starting switch, contacts in the circuit of the
- starting switch winding normally closed by the relay, normally open contacts in the circuit of the running switch winding closable by the relay when operated, means for opening the normally closed contacts and for closing the normally open contacts, and means for operating the said contacts from their normal positions only when the current in the motor circuit is below a predetermined value.
15. In combination, an induction motor, a supply circuit, a transformer, magnetically-operated contacts for first connecting the motor to the supply circuit through the transformer and then connecting the motor directly to the supply circuit, a relay controlling the connection of the motor to the transformer and the connection of the motor to the supply circuit, an operating winding therefor energized by current through the transformer, and means for preventing the return of the relay to its initial position until after the motor is connected directly to the supply circuit.
16. In an electric controller, an alternating current motor, a starting switch, a running switch, operating windings for said switches, means for preventing the simultaneous energization of both windings, and means responsive to the current through the motor for automatically causing the starting switch to open and the running switch to close.

Signed at Cleveland, Ohio, this 14th day of October, A. D. 1912.
